(57) **CLAIM**

The ornamental design for a glitter pencil, as shown and described.

DESCRIPTION

FIG. 1 is front elevation view of the glitter pencil showing my new design;

FIG. 2 is a first end view thereof;

FIG. 3 is a second end view thereof; and,

FIG. 4 is a partial enlarged view thereof.

The eraser portion and the shaft portion of the glitter pencil are lined for color. The broken lines on the band between the eraser and the shaft are shown for information purposes only and form no part of the claimed design.
